UNITED STATES PATENT OFFICE.

NORRIS E. GOODRICH, OF BATTLE CREEK, MICHIGAN, ASSIGNOR TO SANITARIUM AND HOSPITAL EQUIPMENT CO., OF BATTLE CREEK, MICHIGAN.

THERAPEUTIC LIGHT APPARATUS.

Application filed August 1, 1927. Serial No. 209,890.

The main objects of this invention are:

First, to provide an improved therapeutic lamp which is portable and well adapted for use in hospitals, sanitariums and the like and to be adjusted at the side of a bed or cot for treatment of a patient lying thereon.

Second, to provide an improved therapeutic lamp apparatus which has a considerable range of adjustment, which adjustment can be readily effected.

Third, to provide an improved therapeutic lamp apparatus employing a series of arc lamps in which the lamps have a common control means.

Fourth, to provide an apparatus having these advantages which is not likely to get out of repair.

Objects pertaining to details and economies of my invention will definitely appear from the description to follow. The invention is defined in the claims.

A structure embodying the features of my invention is clearly illustrated in the accompanying drawing in which:

Fig. 1 is a front elevation of my improved therapeutic lamp structure.

Fig. 2 is an end elevation looking from the left of Fig. 1.

Fig. 3 is a vertical section on line corresponding to line 3—3 of Fig. 2, parts being broken away for convenience in illustration.

Fig. 4 is a detail section on line 4—4 of Figs. 1 and 5 showing details of the adjusting means.

Fig. 5 is a detail section on line 5—5 of Fig. 4 showing further details.

Referring to the drawing, the embodiment of my invention illustrated comprises tubular standards 1 having cross pieces 2 at their lower ends. Downwardly diverging braces 3 extend from about midway of the standards to the ends of the cross pieces 2. These braces have vertical bottom portions 4 below the cross pieces 2 carrying the caster wheels.

5. The standards are connected by longitudinal bars 6, the top bars being substantially spaced from the upper ends of the standards.

Uprights 7 telescope within the standards and are secured in their adjusted positions by the thumb screws 8. Collars 9 are mount-

ed on the upper ends of the standards as finish members and also to receive the set screws.

I provide a reflector 10 which is elongated and comprised of a cylindrically curved segment. The reflector is supported by the longitudinally projecting spindle-like arms 11 which are secured on the outer side of the reflector by means of the clips 12, the arms being disposed adjacent one edge of the reflector. These arms are adjustably mounted on the uprights 7 by means of the split clamping collars 13. The collars have projecting lugs 14 at one side to receive the clamping screws 15.

On the arms 11 are stop-arms 16 carrying the spaced stops 17 coacting with the uprights 7 to limit the swing of the reflector so that when the clamps are released the reflector will not swing too far in either direction, and prevents the same getting out of control while being manipulated.

In the structure illustrated I provide a pair of lamps, the bottom electrodes 18 being supported in holders 19 carried by the rods 20 and 21 depending within the reflector. The top electrodes 22 are provided with holders 23 carried by the clutch rods 24 projecting through the wall of the reflector. The feed clutches 25 are connected by the links 26 to arms 27 on the rockshaft 28 which is supported in hangers 29. The rockshaft 28 is operatively connected to the armature 30 of the solenoid 31, a common control thus being provided for the lamps.

The lamps are connected in series as described in detail in my application for Letters Patent on arc lamp apparatus filed concurrently herewith. As these features are made the subject matter of such application, they are not described with further detail herein, it being believed that it is sufficient here to point out that the lamps are connected in series and have a common feed or control means.

As these lamps are to be used for the administering of light treatments, it is desired to provide the carbons or electrodes with screens which comprise the holders 31 provided with upwardly projecting arms 32 terminating in fingers 33 detachably engageable with the collars 34 on the electrode holder

supports 20 and 21. These arms 32 have spring clips 35 below the fingers 33 adapted to engage the rods 20 and 21.

With this arrangement the screens can be readily removed when it is desired to adjust the lower carbons or clean the screens.

My improved therapeutic lamp apparatus may be moved about as from cot to cot in a ward, or from room to room, is very simple in structure and not likely to get out of repair, there being comparatively few parts.

The lamps being connected in series and having a common control, they are kept uniformly adjusted; that is, the carbons are adjusted so that one cannot rob another.

I have illustrated two lamps but it will be understood that more may be employed if desired.

I have not attempted to illustrate certain other adaptations and certain modifications which I contemplate as I believe this disclosure will enable those skilled in the art to embody or adapt my improvements as may be desired.

Having thus described my invention what I claim as new and desire to secure by Letters Patent is:

1. In a therapeutic apparatus, the combination of a portable frame comprising spaced tubular standards, cross pieces at the lower ends of said standards, upwardly diverging braces secured to the ends of said cross pieces and to said standards, said braces being extended below said cross pieces and provided with caster wheels at their lower ends, longitudinal bars connecting said standards, the upper longitudinal bar being spaced from the upper ends of said standards, uprights having telescoping engagement with said standards for vertical adjustment, said standards being provided with clamping means for securing said uprights in their adjusted positions, an elongated cylindrically curved reflector, longitudinally projecting arms mounted on said reflector above the center thereof, said uprights having clamping collars on their upper ends for securing said reflector in its adjusted position, a lamp housing mounted on said reflector, and a plurality of arc lamps mounted on said reflector with their control mechanism within said housing and with their electrode supports projecting within said reflector.

2. In a therapeutic apparatus, the combination of a portable frame comprising spaced tubular standards, uprights having telescoping engagement with said standards for vertical adjustment, said standards being provided with clamping means for securing said uprights in their adjusted positions, an elongated cylindrically curved reflector, longitudinally projecting arms mounted on said reflector above the center thereof, said uprights having clamping col-

lars on their upper ends for securing said reflector in its adjusted positions, a lamp housing mounted on said reflector, and a plurality of arc lamps mounted on said reflector with their control mechanism within said housing and with their electrode supports projecting within said reflector.

3. In a therapeutic apparatus, the combination of a portable frame comprising spaced tubular standards, uprights having telescoping engagement with said standards for vertical adjustment, said standards being provided with clamping means for securing said uprights in their adjusted positions, an elongated cylindrically curved reflector, longitudinally projecting arms mounted on said reflector above the center thereof, said uprights having clamping collars on their upper ends for securing said reflector in its adjusted position, stop arms on said reflector arms provided with spaced stops coacting with said uprights for limiting the swinging adjustment of said reflector on said uprights, a lamp housing mounted on said reflector, and a plurality of arc lamps mounted on said reflector with their control mechanism within said housing and with their electrode supports projecting within said reflector.

4. In a therapeutic apparatus, the combination of a portable frame comprising a pair of spaced tubular standards, cross pieces at the lower ends of said standards, upwardly diverging braces secured to the ends of said cross pieces and to said standards, said braces being extended below said cross pieces and provided with caster wheels at their lower ends, longitudinal bars connecting said standards, the upper longitudinal bar being spaced from the upper ends of said standards, uprights mounted on said standards for vertical adjustment, an elongated cylindrically curved reflector, longitudinally projecting arms mounted on said reflector above the center thereof, said uprights having means for securing said reflector in its adjusted position, stops for limiting the swinging adjustment of said reflector on said uprights, a lamp housing mounted on said reflector, and an arc lamp mounted on said reflector with its control mechanism within said housing and with its electrode support projecting within said reflector.

5. In a therapeutic apparatus, the combination of a portable frame comprising a pair of spaced tubular standards, cross pieces at the lower ends of said standards, upwardly diverging braces secured to the ends of said cross pieces and to said standards, said braces being extended below said cross pieces and provided with caster wheels at their lower ends, longitudinal bars connecting said standards, the upper longitudinal bar being spaced from the upper ends of

- 5 said standards, uprights mounted on said standards for vertical adjustment, an elongated cylindrically curved reflector, longitudinally projecting arms mounted on said reflector above the center thereof, said uprights having means for securing said reflector in its adjusted position, a lamp housing mounted on said reflector, and an arc lamp mounted on said reflector with its control mechanism within said housing and with its electrode support projecting within said reflector.
- 10 6. In a therapeutic apparatus, the combination of a frame comprising spaced tubular standards, uprights having telescoping engagement with said standards for vertical adjustment, means for securing said uprights in their adjusted positions, a reflector, projecting arms on said reflector carried by said uprights, said uprights having means for securing said reflector in its adjusted position, stops for limiting the swinging adjustment of said reflector on said uprights, a lamp housing mounted on said reflector, and an arc lamp mounted on said reflector with its control mechanism within said housing and with its electrode support projecting within said reflector.
- 15 7. In a therapeutic apparatus, the combination of a frame comprising spaced tubular standards, uprights having telescoping engagement with said standards for vertical adjustment, means for securing said uprights in their adjusted positions, a reflector, projecting arms on said reflector carried by said uprights, said uprights having means for securing said reflector in its adjusted position, a lamp housing mounted on said reflector, and an arc lamp mounted on said reflector with its control mechanism within said housing and with its electrode support projecting within said reflector.
- 20 8. In a therapeutic apparatus, the combination of a frame comprising spaced tubular standards, uprights having telescoping engagement with said standards for vertical adjustment, means for securing said uprights in their adjusted positions, a reflector, projecting arms on said reflector carried by said uprights, said uprights having means for securing said reflector in its adjusted position, a lamp housing mounted on said reflector, an arc lamp mounted on said reflector with its control mechanism within said housing and with its electrode support projecting within said reflector.
- 25 9. In a therapeutic apparatus, the combination of a portable frame comprising spaced standards, uprights mounted on said standards for vertical adjustment, an elongated cylindrically curved reflector, longitudinally projecting arms mounted on said reflector above the center thereof carried by
- 30 said uprights and adjustably mounted on said uprights, an arc lamp mounted on said reflector with its control mechanism within said housing and with its electrode support projecting within said reflector, and a screen for the electrode detachably mounted on the electrode support.
- 35 10. In a therapeutic lamp apparatus, the combination of spaced vertically adjustable uprights, an elongated cylindrically curved reflector mounted on said uprights for rotative adjustment, the axis being above the center of said reflector, a lamp housing mounted on said reflector, a plurality of arc lamps mounted on said reflector with their control means within said housing and their electrode supports within said reflector, and screens for said electrodes detachably mounted on the electrode supports.
- 40 11. In a therapeutic lamp apparatus, the combination of spaced vertically adjustable uprights, an elongated cylindrically curved reflector mounted on said uprights for rotative adjustment, the axis being above the center of said reflector, a lamp housing mounted on said reflector, and a plurality of arc lamps mounted on said reflector with their control means within said housing and their electrode supports within said reflector.
- 45 12. In a therapeutic lamp apparatus, the combination of spaced vertically adjustable uprights, an elongated cylindrically curved reflector mounted on said uprights for rotative adjustment, a lamp housing mounted on said reflector, a plurality of arc lamps mounted on said reflector with their electrodes projecting within said reflector, and a control mechanism common to all of said lamps mounted within said housing.
- 50 13. In a therapeutic apparatus, the combination of a cylindrically curved reflector mounted for rotative adjustment, the axis being above the center of the reflector, a lamp housing mounted on said reflector above its axis of adjustment, and a plurality of arc lamps mounted on said reflector with their electrodes within the reflector, said lamps being connected in series and provided with a common control mechanism.
- 55 14. In a therapeutic lamp apparatus, the combination of a vertically adjustable frame, a reflector mounted on said frame for rotative adjustment, a lamp housing mounted on said reflector, a plurality of arc lamps mounted on said reflector with their control means within said housing and their electrode supports within said reflector, and screens for said electrodes detachably mounted on the electrode supports.
- 60 15. In a therapeutic lamp apparatus, the combination of spaced vertically adjustable uprights, an elongated cylindrically curved reflector mounted on said uprights for rotative adjustment, a plurality of arc lamps mounted on said reflector with their elec-

trodes within the same, and a control mechanism common to all of said lamps mounted on the outside of said reflector.

16. In a therapeutic apparatus, the combination of a reflector mounted for adjustment, a lamp housing mounted on said reflector above its axis of adjustment, and a plurality of arc lamps mounted on said reflector with their electrodes within the reflector, said lamps being connected in series and provided with a common control mechanism.

17. In a therapeutic lamp, the combination of a vertically adjustable-supporting frame comprising spaced uprights, an elongated transversely curved reflector mounted between said uprights for tilting adjustment on a longitudinal axis disposed above the center of the reflector, a plurality of arc lamps mounted on said reflector with their electrodes arranged within said reflector and in substantially the same relation

relative to its reflecting surface, and a control mechanism common to all of said lamps mounted on the outside of said reflector.

18. In a therapeutic lamp, the combination of a supporting frame, an elongated reflector mounted for tilting adjustment on a longitudinal axis disposed at the top of the reflector, a lamp housing mounted on said reflector to project above and in the longitudinal plane of its axis, a plurality of arc lamps mounted on said reflector within said housing with their electrodes within the same and in substantially the same relation relative to the reflecting surface, said lamps being connected in series and provided with a carbon feed means common to all of the lamps.

In witness whereof I have hereunto set my hand.

NORRIS E. GOODRICH.
